(57) **CLAIM**

The ornamental design for a camera, as shown and described.

DESCRIPTION

FIG. 1 is a top, front and side perspective view of a camera showing our new design;

FIG. 2 is a front elevational view thereof;

FIG. 3 is a top plan view thereof;

FIG. 4 is a side elevational view thereof from the right of FIG. 2;

FIG. 5 is a top, front and side perspective view thereof, with the light reducing panel shown in a lower position;

FIG. 6 is a front elevational view thereof;

FIG. 7 is a top plan view thereof; and,

FIG. 8 is an enlarged fragmentary front elevational view of the light reducing panel of FIG. 2.

The parts shown in broken lines are only to illustrate the environment and are not claimed.
